UNITED STATES PATENT OFFICE

HENRY MATHIS, OF CLOQUET, MINNESOTA

LINE GRIP

Application filed May 28, 1931. Serial No. 540,535.

This invention relates to line grips or holders and refers especially to one adapted for use in the holding of an anchor line for a row boat or the like, though, obviously, may be used for gripping or holding a line under various circumstances.

The embodiment here illustrated is of such a device for use in holding an anchor line of a row boat and the principal object of the invention is to produce a more practical and efficient device of this character.

Another object is to produce such a device capable of adjustment for various sized lines, and also one adjustable to various conditions of operation.

Still other objects and advantages of the novel structure and arrangement of parts will appear in the following description of the invention.

20 Referring now to the accompanying drawings, forming part of this application, and wherein like reference characters indicate like parts:

Figure 1 is a central sectional view dividing the device into two equal halves, with the exception of the upright standard therefor which is shown in elevation; and

Figure 2 is a top plan view of the completely assembled device.

30 1 represents a metal bar having a plurality of screw or bolt holes therein for fixing engagement to, for example, the bow of a pleasure boat, such as a row boat or the like. Through the outer end of the bar 1 extends the pintle 2 of the upright support 3, the latter being flat upon opposite sides and designed to fit snugly intermediate of the spaced flat walls of the housing of the grip. These walls are illustrated at 4 and 5, they 35 being pivotally attached as at 6 to said upright support or member. Through these side walls are formed a group, preferably of three holes indicated at 7, there being one in this illustration occupied by the bolt or pin 8 and all of which holes are registerable with the bottom portion of the slot 9 in the upper end of the support or standard 3. This arrangement provides for the adjustment of the housing on the standard; that 45 is to say the pin 8 may be placed through

any one of the three holes desired which would determine the preferred angle for the housing, and when in the desired position may be tightly held by tightening the thumb nut illustrated at 6'. A suitable nut 10 is 55 provided below the bar 1 and on the pintle 2 of the support, there being a hole 11 through the pintle below the nut, so that the nut may not be drawn tight, thus permitting of the grip rotating at will while holding 60 to the angular stress of the rope being held, which, in this instance, is the anchor line 12 attached as at 13 to a suitable anchor 14.

Intermediate of the side plates 4 and 5, above and just slightly forwardly of the upper end of the upright support, is mounted the roller like sheave 15, over which the anchor line 12 is payed, and thence it extends rearwardly intermediate of the gripping dogs 16 and 17, the former being pivotally mounted 65 intermediate of the side plates 4 and 5 as at 18, and the latter pivotally mounted on the adjustable eyebolt 19. The pivotal support of the dog 17 constitutes the pin 20 passing through the eye of the bolt 19 and also 70 through both side plates, and for which through passage a vertical slot indicated at 21 is provided in each plate so that the dog 17 may be raised or lowered to accommodate 75 various sized lines. This raising or lowering is accomplished by the circular thumb nut 22 80 extending upon both sides through the side plates so that the same may be readily rotated for vertical adjustment of the bolt 19; said nut being knurled for convenient manipulation. Both dogs are preferably made of substantially channel shaped material, for strength and convenience in manufacture, and the one 16 has an elongated counterbalancing shank so that the dog is normally held in proper gripping position. 85

It is obvious from the above described construction that forward motion of the line to any material extent is automatically prevented by the cooperative action of the jaws 16 and 17, and that when opposite stress is put upon the line in pulling it inboard, the jaws instantly free their hold thereupon. If it is desired to slack off the line without the jaws acting thereupon, all that is necessary 90 95 100

is to keep the line well elevated to prevent such gripping.

The entire housing is preferably held together by suitable rivets indicated at 23 so that the entire assembly is exceptionally compact and convenient for transportation, attachment, and manipulation.

As illustrative of the convenience of the device, apart from that which is obvious in raising and lowering an anchor, attention is directed to the following: Assuming an individual, alone in a rowboat, wishes to land upon a sloping shore or beach, this device is particularly convenient in that he may approach the shore, advance to the bow of the boat, heave the anchor ashore, then return to the stern of the boat which will materially reduce the draft at the bow, when, by pulling on the free end of the anchor line through the grip, he may readily pull the boat well up onto the shore. While this is but one illustration of the convenience of such a device many others may result from its use under various circumstances.

It is to be noted that the vertical corrugations or knurling of the thumb nut have a double function which includes the better grip for turning same, as well as the engagement with the edges of the holes through the plates 4 and 5, which prevents accidental turning of same, as the nut is comparatively loose in said holes.

Also the depending handle like portion of the dog 16 is considerably narrower in its lower end than at its upper end so as to prevent binding or frictional contact with the sides in the event of the boat to which it is applied listing and thereby supporting the grip in inclined position; resulting in the dog 16 operating as freely in inclined position as when upright.

Having thus described my invention, what I claim and desire to secure by Letters Patent, is:

1. A line grip of the type described comprising a housing pivotally carried upon a pivotal support, a roller within the housing forwardly of the pivotal support thereof, and a pair of pivoted gripping jaws upon the opposite side of the pivotal support, whereby a line may be passed over the roller and between the jaws, and be manipulated remote from the grip at any desired angle.

2. A line grip of the type described comprising a housing pivotally carried upon a pivotal support, said housing being open throughout its entire marginal edges, a roller within the housing forwardly of the pivotal support, a pair of jaws within the housing rearwardly of the support, whereby a line may be passed over the roller and between the jaws and manipulated remote from the grip at any desired angle.

3. A line grip of the type described including a roller intermediate of two spaced

plates, two line gripping jaws pivotally mounted between the plates, the uppermost one being vertically adjustable to accommodate different sized lines, and both jaws having free oscillatory motion.

4. A line grip of the type described including spaced side plates, a pair of pivotally mounted line gripping jaws intermediate of said plates, means for adjusting the spaced relation of said jaws to accommodate different sized lines and an adjustable pivotally mounted means for supporting said grip.

5. A line grip including spaced side plates, spaced line gripping jaws pivotally mounted within said plates, means for adjusting the spaced relation of said jaws, and an adjustable pivotally mounted support for said grip.

In testimony whereof I affix my signature.

HENRY MATHIS.
